UNITED STATES PATENT OFFICE.

RUSSEL H. WHEELOCK, OF DAYTON, OHIO.

DESIGN FOR A PIN-TRAY.

50,543.

Specification for Design.

Patented Mar. 27, 1917.

Application filed September 5, 1916. Serial No. 118,588. Term of patent 3½ years.

To all whom it may concern:

Be it known that I, RUSSEL H. WHEELOCK, a citizen of the United States, residing at Dayton, in the county of Montgomery and State of Ohio, have invented a new, original, and ornamental Design for Pin-Trays, of which the following is a specification, reference being had therein to the accompanying drawing.

The figure is a plan view of a pin tray, showing my new design.

I claim:

The ornamental design for a pin tray, as shown.

In testimony whereof I affix my signature.

RUSSEL H. WHEELOCK.
